UNITED STATES PATENT OFFICE.

HENRY H. GOVE, OF BIDDEFORD, MAINE, ASSIGNOR OF ONE-HALF TO HOWARD R. WHITEHEAD, OF SACO, MAINE; CHARLOTTE M. GOVE ADMINISTRATRIX OF SAID HENRY H. GOVE, DECEASED.

THREAD TENSION DEVICE.

Application filed May 27, 1919. Serial No. 300,098.

To all whom it may concern:

Be it known that I, HENRY H. Gove, a citizen of the United States, residing at Biddeford, in the county of York and State of Maine, have invented certain Improvements in Thread Tension Devices, of which the following description, in connection with the accompanying drawings, is a specification, like reference characters on the drawings indicating like parts in the several figures.

This invention relates to thread tension devices of the character used in winding, spooling and other machines, to maintain a tension or frictional drag on the thread, yarn, twine, or similar material handled by the machine. For convenience this material will be referred to hereinafter as "thread."

Tension devices are used very extensively on such machines as those just mentioned and the present forms have, among other objections, the particular disadvantage of frequently becoming so clogged with lint or other foreign material carried by the thread as to interfere very seriously with their normal functions. These accumulations of lint vary the tension applied to the thread, sometimes breaking the thread and frequently putting the tension device completely out of commission by wedging apart the members that bear on the thread so that they fail to exert any friction or tension on the thread. The present invention aims to devise a tension device which will automatically maintain itself clear of accumulations of lint or other foreign material, which will maintain a substantially uniform tension on the thread at all times, in which the degree of tension can be readily adjusted, which can be economically manufactured and which can be quickly and conveniently threaded.

The invention also is directed to the improvement of the means for supporting the bobbin or thread supply and to other features which will be readily understood from the following description when read in connection with the accompanying drawings and will be pointed out more particularly in the appended claims.

Referring now to the drawings,

Figure 1 is a view, partly in side elevation and partly in cross section, showing an apparatus embodying this invention;

Fig. 2 is an angular view on a larger scale 55 showing the thread tension device illustrated in Fig. 1, some of the parts being broken away to illustrate more clearly the details of construction;

Fig. 3 is a cross sectional view substantially on the line 3—3, Fig. 1;

Fig. 4 is an angular view, partly in cross section, illustrating a novel form of bobbin holder;

Fig. 5 is an angular view showing another 65 embodiment of the invention; and

Fig. 6 is a vertical cross sectional view through the head of the tension device shown in Fig. 5 illustrating on a somewhat larger scale the details of construction. 70

Fig. 1 of the drawings shows the invention applied to a spooler. The apparatus shown comprises a bracket 2 supported in a block 4 which is mounted on a bar 6 with which these machines usually are provided, a set screw 8 being employed to bind the block on the bar. The bracket is usually mounted in a slightly inclined position, substantially as shown in Fig. 1, and the thread tension device is supported at the forward 80 or left hand end of the bracket, as the parts appear in Fig. 1. At the opposite end of this bracket a support is provided for the bobbin or cop 10, or other source of thread supply, hereinafter referred to as a "bobbin."

This support, as best shown in Fig. 4, consists of a spindle 12 secured at one end in an arm 14 extending at substantially right angles from the rear end of the bracket arm 90 2. The bobbin spindles 10 are drilled longitudinally from end to end to provide a bore therein. These bores vary somewhat in diameter and one of the objects of this invention is to provide a bobbin support that will accommodate these variations.

The spindle 12 is considerably smaller in diameter than the smallest bore and it is provided at its free end with a removable tip 16 tapered, as shown in Fig. 4, and threaded on to the end of the spindle 12. A U-shaped spring 18 consisting of a piece of resilient wire extending through a transverse hole in the shank of the spindle 12 has its legs bent to extend substantially parallel to the axis 100 of the spindle, the extremities of these legs being turned inwardly toward each other.

The tip 16 centers the bobbin on the

spindle and the legs of the spring 18 are compressed or forced toward each other by engagement with the wall of the bore of the bobbin spindle 10 so that it provides considerable friction between the spindle and the spring resisting the removal of the bobbin. To accommodate any wide variation in the diameter of the bores of the bobbins, the tips 16 may be easily removed and replaced by one of suitable size. This construction can be very economically manufactured, the tips 16 are easily changed, and the spring 18 yields sufficiently to hold bobbins having very substantial variations in the diameters of their bores. In using the device the bobbin is slipped on the spindle 12, sliding freely over the tip 16, and is wedged on to the spring 18, the legs of this spring being forced toward each other by their engagement with the walls of the bore in the bobbin. Since the spring engages the bore of the bobbin for a substantial distance it exerts ample friction on the bobbin to prevent it from accidentally becoming loosened.

The thread tension device comprises a rod or wire 20 having its lower end fixed in the bracket 2 and extending more or less in an upright direction, depending upon the adjustment of the bracket arm. A small U-shaped fixture 22 is supported on the upper end of the rod 20 and in turn supports another rod 24 extending downwardly parallel to the rod 20. These rods may be made of relatively heavy wire. They are spaced apart in the direction of travel of the thread T so that they engage opposite sides of the thread, any given point on the thread coming in contact with them successively. Close beside the rod 24 is a plate 26 which, as best shown in Fig. 3, is provided with an eye at its upper end to receive a headed pin 28 supported in the fixture 22 and forming a pivot on which the plate 26 can swing toward and from the rod 24. A threaded rod or bolt 30 secured rigidly to the upper part of the plate 26 projects at right angles thereto and co-operates with the plate to form a bell crank lever moving on the pin 28 as a fulcrum. A weight 32 has a hole bored eccentrically therethrough and is threaded on the bolt 30, this construction providing for the convenient adjustment of the weight longitudinally of the bolt to vary more or less its effective leverage and thus to vary the pressure with which the plate 26 will be held against the rod 24. Due to the fact that the mass of the weight 32 is eccentrically disposed with reference to the rod 30, the force of gravity will tend to hold the weight in its adjusted position. That is, it will prevent the weight from rotating on the rod due to vibration of the machine. The lower part of the rod 24 is bent, as clearly shown in

the drawings, to provide inclined portions 34 and the end of the rod is bent to form a pig tail guide 36 lying between the rod 20 and the bobbin 10. Another wire 38 has one end fastened in a bracket head 40 formed on the end of the bracket arm 2 and its opposite end is fastened at 42 to the inclined part 34. These parts 36 and 38 form thread guides at opposite sides of the parts that apply the tension to the thread. The bracket head 40 is curved upwardly and over the parts of the thread tension device above described and forms both a hood or shield for them and also a guide for the thread.

It will be evident from an inspection of Fig. 1 that the natural operation of threading the device after the bobbin has been placed on the support or spindle 12 is to swing the thread T under the inclined parts 34 and 38, over the shield 40, and then to carry it over the transverse bar 44 to the spool 46. The pull of the spool on the thread draws the thread upwardly along the lower surface of the inclined wire members 34 and 38 into the pig tail guide 36 and into the notch or angle formed between the inclined wire 38 and the vertical face of the part 40, as clearly shown in Figs. 2 and 3. This operation also pulls the thread into position between the plate 26 and the rod 24. The threading operation thus is very simple and is, in a sense, automatic since it is effected partly by the pull exerted on the thread by the spool.

It will be appreciated that, due to the very open construction of the thread tension device and also to its position, it is impossible for it to clog up with lint or accumulations of foreign material carried by the thread. Any such material removed from the thread by its passage through the tension device falls clear of the device since there is nothing on which it can lodge as it drops from the thread. The most serious objection to the present thread tensions therefore is obviated. It will also be appreciated that the apparatus can be manufactured very economically, that it will wear for a very long time, and that the adjustment of the tension on the thread can be effected very easily and conveniently simply by turning the weight 32 on the bolt 30.

A somewhat different embodiment of the invention is illustrated in Figs. 5 and 6 the various parts in these figures corresponding to those shown in Figs. 1 to 4, inclusive, being designated by primed reference numerals. The general arrangement of parts is like that above described, but the rod 24' has a roll 50 rotatably mounted thereon against which the plate 26' bears. The roll is supported at its lower end by a tapered collar 51 which is driven on the rod 24' and any upward movement of the

roll is limited by a collar 52 also fixed on the rod 24'. The thread runs through the pig tail guide 36' between the roll 50 and the plate 26', under the shoulder on the bracket 40', and over this bracket, as shown in Fig. 1, the drag of the thread on the roll rotating the roll. Preferably the upper end of the roll is counterbored, as indicated at 53, and this counterbored recess is filled with graphite to lubricate the roll. A collar 54 on the rod 20' prevents the thread from climbing up along this rod to a point above the upper end of the roll.

Under some conditions there may be a tendency for the plates 26 or 26' to chatter slightly, particularly when the thread is travelling at high speed. I find that this tendency can be overcome and that a very uniform tension can be maintained on the thread by resiliently supporting the weight which produces the tension or frictional drag. Such an arrangement is illustrated in Figs. 5 and 6, in which the weight 55 is supported from the bolt or rod 30' by a light tension spring 56. This spring takes up or absorbs the vibrations that apparently produce the chattering effect just mentioned and at the same time it appears to reduce the shock to which the thread is subjected due to variations in its diameter. This arrangement thus reduces materially the breakage which is particularly likely to occur in spooling fine thread or yarn, and it produces a smooth yielding, uniform tension that is very desirable in devices of this character. The roll 50 also contributes to this result.

In order to prevent the thread from sliding off the end of the bracket head 40', a flange 57 is formed on the edge of this head, as clearly shown in Figs. 5 and 6. In this construction, also, the spindle 12' is provided with two of the U-shaped springs 18' located at right angles to each other so that they tend to effect an accurate centering of the bobbin on the spindle. It is obvious that the various features of the two forms of the invention can be used interchangeably as desired.

While I have herein shown and described the best embodiment of the invention of which I am at present aware, it will be understood by those skilled in this art that this embodiment may be modified in many par-

ticulars without departing from the spirit or scope of the invention.

What is claimed as new, is:

1. A thread tension device comprising a part having a curved surface, a plate having a part extending substantially parallel with said surface, a pivot supporting said plate for movement to carry said part into and out of engagement with said surface, a rod projecting from said plate at an angle thereto, and a weight adjustable on said rod, said weight acting to swing said plate toward said rod.

2. A thread tension device comprising two thread engaging members, means for guiding the thread between them, and means for relatively moving said members toward each other to pinch the thread more or less as it passes between them, said means comprising a weight and a bolt on which said weight is threaded, the mass of said weight being eccentrically disposed with reference to the bolt whereby it will be held in adjusted position longitudinally of the bolt by the influence of gravity on said eccentrically disposed mass.

3. A thread tension device comprising two rods positioned to engage opposite sides of the thread and spaced apart in the direction of travel of the thread, a plate mounted to bear against one of said rods, means for yieldingly urging said plate toward the latter rod, thread guiding devices arranged to engage and guide the thread both before it comes in contact with said rods and after it leaves them, and a hood covering said rods and plate and over which the thread is guided.

4. A thread tension device comprising a roll, a plate mounted to bear against said roll, means for guiding a thread between said plate and roll, and means tending constantly to relatively move said roll and plate to pinch the thread between them.

5. A thread tension device comprising a roll, a plate mounted to bear against said roll, means for guiding a thread between said plate and roll, and a weight acting to relatively move said roll and plate to pinch the thread between them.

In testimony whereof I have signed my name to this specification.

HENRY H. GOVE.
